INVENTOR.

BY *Neal Merritt Faulds,*
Mark S. Ackerman.
ATTORNEY.

Patented July 10, 1928.

UNITED STATES PATENT OFFICE.

NORVAL MERRITT FAULDS, OF CLEARWATER, FLORIDA.

DEVICE FOR PORCH CURTAINS.

Application filed July 21, 1927. Serial No. 207,449.

This invention relates to improvements for holders of the edges of porch curtains or other curtains, and has for an object the provision of novel means for guiding the edges of curtains as they are adjusted and for thereafter creating a waterproof joint between the curtain and the guide, while at the same time maintaining the curtain in a taut state.

10 With the foregoing and other objects in view, the invention consists in the details of construction, and in the arrangement and combination of parts to be hereinafter more fully set forth and claimed.

15 In describing the invention in detail, reference will be had to the accompanying drawings forming part of this application, wherein like characters denote corresponding parts in the several views, and in 20 which—

Figure 1 illustrates a view in perspective of a fragment of a curtain, showing a guide and clamp embodying the invention;

25 Figure 2 illustrates a similar view with the clamp in operative position;

Figure 3 illustrates a vertical sectional view of the guide and parts associated with it; and

30 Figure 4 illustrates a perspective view of one of the clamping elements.

In these drawings, 10 denotes any suitable type of casing with relation to which the device is mounted, it being understood that the parts are duplicated for each edge of 35 the curtain.

35 In the present embodiment of the invention, a molding or angularly formed plate 11 is attached to the casing, and at the edge remote from the edge which is anchored to 40 the casing, the plate is shaped to form a guide and clamping portion 12. Near the edge remote from its anchorage to the casing, the plate is connected to a channeled plate 13 by fastenings 14, such as screws, 45 bolts, or the like, which engage a flange 15 of the said channeled plate. The channeled plate 13 acts as a guide for a movable clamping element 16, which element preferably is provided with side flanges 17 and 18 which 50 engage or are confined by the flanges of the channeled plate 13, and the channeled plate is, of course, intended to be anchored to the casing.

55 A curtain 19 has its edges projecting between the clamping element 16 and the guide and clamping portion 12, and means are

provided for moving the element 16 toward and away from the guide and clamping portion 12 and, in this adjustment, it is intended that the curtain shall be flexed, as shown 60 in Fig. 2, in order that the curtain will be drawn taut and then clamped.

As a means for moving the clamping element 16 toward and away from the portion 12, a bell crank lever 20 is provided and it 65 is oscillatable on a pivot 21 anchored to the flanges of the plate 13. The short arm of the bell crank is connected to a pivot 22 secured in apertures, such as 23, in the flanges of the clamping element 16, and the said 70 flanges of the clamping element have recesses 24 constituting clearances in order that the clamping element may be moved with relation to the flanges of the plate 13. The plate 13, as well as the casing, is provided with slots 25 and 26, respectively, and these constitute clearances for the operation 75 of the bell crank.

When the bell crank occupies the position in which it is illustrated in Fig. 1, the clamping members are separated, whereas when the bell crank is moved to the position shown in Fig. 2, the curtain is flexed and clamped, 80 as fully shown.

The clamping element 16 is also provided 85 with supplemental hangers or links comprising plates 27 arranged in pairs and oscillatable on a pivot 28 which are also anchored in flanges of the plate 13, whereas their opposite ends are oscillatable on pivots 29 applied to apertures similar to the apertures 90 23 in the flanges of the clamping element and, of course, the flanges of the clamping element will be provided with recesses, such as 24, in order that the flanges of the clamping 95 element may move with respect to the pivot 28.

From an inspection of the drawing and the foregoing description, it will be apparent that after the parts are assembled and the curtain has its edges inserted between the clamping members, the operation of the bell crank will adjust the parts to the desired position for accomplishing the result sought.

100 Preferably, the relation of parts is such that the short arm of the bell crank is of less length than the width of the space between the curtain and the guide and clamping portion, as it is desirable that the axis of the pivot 22 shall rise above the axis of 105 the pivot 21 at the time the curtain is clamped in order that the bell crank will be 110

held against movement, except when force is applied to it.

While the device has been described as particularly applicable to a porch curtain, the inventor does not wish to be limited to this use, as it has been found in practice that the device may be used with success with curtains of various types.

I claim:

10 In a porch curtain or other curtain, a plate having a portion adapted to coact with a clamping element, the said portion having a curtain engaging flange, a clamping ele-

ment movable with relation to the said flange, the said clamping element comprising a plate having side flanges with apertures and recesses, means for moving the said clamping element comprising stationary pivots, pivots on the clamping element arranged in pairs, and rigid elements applied to the pivots and operative to swingingly support the clamping element, including means for imparting motion to said clamping element.

NORVAL MERRITT FAULDS.
